UNITED STATES PATENT OFFICE.

JERE L. WENTZ, OF PASSAIC, NEW JERSEY.

MASSAGE MACHINE.

Application filed September 22, 1925. Serial No. 57,825.

My invention relates to improvements in massage machines and the object of my invention is to provide a machine adapted to massage or knead the human body and parts thereof.

I accomplish this object by the device illustrated in the accompanying drawings in which is shown the preferred form of a device embodying my invention, and in 10 which

Figure 1 is a vertical sectional view of the device,

Figure 2 is a side view,

Figures 3 and 4 are views showing the 15 device in operation, and

Figure 5 is a detail of the snap fastening means.

Similar characters of reference refer to similar parts throughout the several views.

20 My device preferably includes a frame 1 with a rotatable drum 2 having peripheral rollers and a motor 4 by which the drum 2 is rotated.

The frame may be constructed of uprights 25 5, with cross bars 9 and 10. This frame may be conveniently constructed of iron piping. On the uprights 5 are provided supporting rails 12 and 13 carrying a hollow bar 6 on the underside of which is provided

30 a driving motor 4 and pulley 14 to which is attached a worm gear through which the power is transmitted to a geared driving wheel 15 on the drum 2. This drum 2 includes two side wheels 16 and 17 with connecting bars 18, 18 and is rotatable on the bar or axle 6 thru which the current feed wire runs to the motor 4 as shown. Loose rotatable rollers 19, 20 of any desired shape are mounted peripherally on the wheels 16 35 and 17. For this purpose I prefer to provide bearing pins 19' and 20' respectively on the rollers 19 and 20.

These pins are seated in sockets 22, 22 in the wheel 16 adjacent its marginal edge and 45 in open sockets 23, 23 in the wheel 17 adjacent its marginal edge. The open sockets 23 are adapted to be closed by means of spring clips 24 on the wheel 17 whereby the rollers 19 are detachably seated and may 50 be removed and replaced, as desired. The spring clip 24 is shown in Figure 5 and also at 24 in Figure 2. Tho each roller is so held in the wheel 17, it is considered necessary to show only a single roller so 55 held.

I have found it desirable in some cases to

vary the form of the rollers and I have therefore shown in the drawings two forms of these rollers. In one form 19, I have shown rollers having flared end sections 24² 60 and an intermediate cylindrical section 24'; in another form 20, I have shown rollers having two broad annular grooves 25 and 25' and a raised intermediate section 26 but these forms may be varied as conditions 65 may require or individual taste may dictate.

I also provide, when desired, a removable back rest 27 which may be carried on removable posts 28, 29 inserted in the frame.

Electric current for driving the motor 70 may be supplied from the house current or from any convenient source and is controlled by means of a switch (not shown) in the usual well known manner.

The device being thus assembled, the 75 motor is started whereby the drum carrying the rollers will be caused to revolve.

The part of the body to be acted upon is then brought into contact with the rollers causing them to revolve whereby a gentle 80 kneading or massaging action will be received. The person to be operated upon may be seated as shown in Fig. 3 upon the revolving drum or may lie upon it or may rest a limb as shown in Fig. 4 or other part 85 of the body thereon as desired.

Having thus described my invention, what I claim is

1. In a massage machine the combination of a frame, an axle thereon, side wheels journaled to rotate on said axle, one of said wheels having peripheral sockets therein, the other said wheels having peripheral open sockets therein, rollers loosely mounted in said sockets between said wheels and 90 spring clips on said second mentioned wheel adjacent and extending into said open sockets whereby said rollers are removably held in said sockets.

2. In a device of the character described 100 the combination of a pair of spaced frame members, a bar connecting said frame members, a pair of wheels journaled substantially at the ends of said bar to rotate thereon rollers on the peripheral margin of said 105 wheels, a gear fixed to the inner side of one of said wheels, a motor supported by said bar between the spaced wheels and gear means connecting the first mentioned gear and said motor.

3. In a device of the character described 110 the combination of two side frame members

having a detachable back mounted thereon, an axle supported by said frame members, a motor supported by said axle, a pair of spaced wheels journaled to rotate on said axle, connecting bars between said wheels, gear means operatively connecting said motor and said wheels, diametrically opposed sockets around the periphery of said wheels and rollers having pins thereon adapted to fit in said sockets.

4. In a massage machine the combination of a frame, an axle supported thereby, spaced wheels journaled to rotate on said axle, a gear fixed to one of said wheels on

the inner side thereof, a motor mounted on said axle and gear means operatively connecting the motor and first mentioned gear, connecting bars between said wheels, sockets diametrically opposed around the peripheries of said wheels, rollers having pins mounted in the ends thereof to seat in said sockets, the sockets in one of said wheels being open and having spring means to retain the said pin in its socket.

In testimony whereof, I have signed my name to this specification this 26th day of August 1925.

JERE L. WENTZ.
